2 SHEETS—SHEET 2.

UNITED STATES PATENT OFFICE.

GEORGE W. PETTEY, OF ALEXANDRIA, VIRGINIA, ASSIGNOR TO PETTEY ELECTRICAL INDICATOR SIGNAL COMPANY, OF ALEXANDRIA, VIRGINIA, A CORPORATION OF VIRGINIA.

ELECTRIC SEMAPHORE-SIGNAL.

No. 913,974.

Specification of Letters Patent.

Patented March 2, 1909.

Application filed September 21, 1908. Serial No. 453,899.

To all whom it may concern:

Be it known that I, GEORGE W. PETTEY, a citizen of the United States, residing at Alexandria, in the county of Alexandria and State of Virginia, have invented certain new and useful Improvements in Electric Semaphore-Signals, of which the following is a specification.

My invention is in the nature of an improved electric semaphore signal, designed more particularly for road crossings at railroad tracks, but applicable as a signal for any purpose whatever.

It relates to that form of semaphore signal in which the arms of the signal revolve from the action of an electric motor, whose circuit is controlled by the car or train as it nears the point to be protected. It has been common to provide a revolving signal of this class which operated through a normally closed circuit which kept the arms normally revolving during the period of safety and which for danger were brought to a standstill. When such normally revolving signal was stopped for danger, one of two difficulties was encountered; either, the revolving signal required to be instantly stopped, which gave a damaging jar to the heavy revolving arms and their gears, or else the revolving arms came to a standstill so slowly, owing to the momentum of the arms, that for a considerable time after the danger adjustment was made the revolving arms would, by revolving, continue to falsely indicate safety at or near the moment of crossing. Furthermore, a danger condition is much more certainly presented to the unwary by the active flight of the arms, than by the quiescent or stationary attitude of the arms.

My invention consists in the novel construction and arrangement of a revolving semaphore signal of this class, in which an open circuit is employed, the normal safety condition being indicated by a stationary condition of the arms and the danger condition being obtrusively indicated by the active flight of the arms in revolving during a limited period only as the train passes the crossing. This limited period is what I term a limited-continuous revolution period, the power transmitting mechanism of the signal being so arranged as to trip a circuit breaker after a limited time and so stop the motor and bring the revolving arms to a standstill with a gradual slowing up of the revolving

arms which, occurring after the passage of the train over the crossing, can involve no danger on the one hand, and no damaging strain on the mechanism from sudden stopping on the other hand.

My invention also consists in the novel construction and arrangement of the semaphore arms in combination with the actuating devices and stop mechanism and also further in the construction and arrangement of the operating mechanism as hereinafter more fully described.

In the drawings Figure 1 is a perspective view of my signal located at a railroad crossing. Fig. 2, is a diagram of the circuits. Fig. 3, is a perspective detail view of the shaft and one of the semaphore arms. Fig. 4, is a cross section through the light-box of the semaphore arm. Fig. 5, is a top plan view of the semaphore box and connected arms. Fig. 6, is a vertical cross sectional view taken on line 6—6 of Fig. 5. Fig. 7, is a vertical cross sectional view taken on line 7—7 of Fig. 5, and Fig. 8, is a detail view of the bell-ringing mechanism.

In the drawing, Fig. 1, A A¹ are the right and left tracks of a double track railway, B is a road crossing, C is a post bearing my revolving signal and D is a box mounted on the post and containing the electro-mechanical motor mechanism for imparting a limited-continuous rotation to the semaphore arms E E. The post C and signal devices are located at the junction of the road crossing. At a suitable distance therefrom—say 1000 feet—is located a second post C¹ which is beside the track on which the cars approach the crossing. Along the edge of one of these rails is located a depressible shoe d, which is adapted to be struck by the wheels of the passing car and which, when depressed, effects electrical contact with a terminal of the wire a leading to the semaphore box D. Any kind of a depressible shoe forming a track switch may be employed. T is the trolley wire and b is a wire leading from the same to the signal box D, while c is another wire leading from the said box to the rails and ground.

The signal box D, Figs. 5, 6, and 7, contains an electric motor M whose armature shaft bears a pinion m engaging a larger gear wheel m¹ to which is rigidly attached a pinion m² which in turn engages a larger toothed gear m³ fixed rigidly on a shaft 5, which car-

ries outside the box the semaphore arms E E. The gears m to m^3 are straight-toothed parallel spur gears for imparting a diminished speed from the motor to the shaft of 5 the semaphore arms, which shaft is at right angles to the plane of the gears and parallel to the axis of the motor. On the hub of the gear m^1 is a crank or eccentric S, Figs. 5 and 8, which, by its rod S¹ connects with the 10 crank arm S² fixed rigidly on a rock-shaft S³, which passes through the wall of the box and on the outside bears a rigidly attached hammer arm S⁴ which, as the shaft is rocked, strikes against a gong bell R, which incloses 15 the same, giving a continuous audible alarm as long as the gears are rotating.

The semaphore shaft 5 passes through the opposite side of the box and carries the semaphore arms E E. These consist, see 20 Figs. 3 and 5, of two shank portions 1, 1, of iron pipe whose inner ends are screw-threaded and turned into the opposite screw-threaded sockets of a four-way coupling 2, the rotary axis 3 of the semaphore arms being rigidly connected by set-screw 4, to a short sleeve 3₁ which is turned into one of the screw-threaded sockets of the four-way coupling 2. On the outer side of each hollow shank is secured a web plate 6, and extending 30 along its edges, in a plane at right angles thereto, is a marginal plate 7, which at the outer end is widened at 7^a to form a hollow light-box whose faces are closed by glass panels 9 and outside of which is a protecting cage 8 of stout woven wire to protect the glass from breakage by sticks and stones. Within each light-box is a cluster of two or more incandescent electric lamps 10, connected to circuit wires 11 and 12. These 35 circuit wires extend through the hollow shanks 1, 1, to the central coupling 2 and thence proceed axially through the hollow shaft 5 to two insulated metal rings J K, which form the terminals of an electric circuit 40 through both clusters of lamps in the two semaphore arms. Brushes, or carbon contacts, J¹, K¹, Figs. 6 and 7, press upon these rings and direct a shunt circuit through the lamps, as hereafter described. The 45 fourth opening of the coupling 2 is provided with a detachable screw cap 2^a through which access is afforded for wiring.

I will now describe the means for continuing the action of the motor after the closure 55 of its initial starting circuit, and stopping the revolution of the semaphore after the car has passed the crossing, reference being had to Figs. 5, 6 and 7. On the semaphore shaft 5, see Fig. 6, is formed a worm L, which engages 60 a vertical worm wheel N located above the shaft and sustained upon a post P. Loosely hung about the axis of the worm wheel is one or more weighted arms O, O¹, and projecting laterally from the worm wheel is a pin n 65 which, as the worm wheel revolves, lifts and

turns up a weighted arm until the latter passes the vertical, at which time said arm drops and imparts a hammer blow to a tripping latch H, which stops the action of the motor, as hereafter described. 70

On the opposite side of the box from the spur gears is mounted an electro-magnet F, beneath, which is pivoted at 17 an armature lever G, bearing on the upper side of its outer end a contact face g and normally 75 gravitating to a position of rest on a pin g². The tripping-latch H is hung in a vertical position upon widely separated horizontal pivots h and its middle swelled-out portion is held out into the path of the arm O by a 80 spring h¹ located between the latch H and the wall of the box. The lower end of latch H has a beveled-face catch h² which is adapted to catch and hold the armature lever G in its elevated position, as indicated by dotted 85 lines in Figs. 6 and 7, whenever said armature lever is lifted by the electro-magnet F. When so lifted the contact g on the end of the lever strikes the vertically movable contact pin i playing vertically in a barrel I, 90 suspended by a head and held down in resilient relation by a spiral spring i¹. The barrel I is connected by a wire 20 to a permanent-ground connection which is established whenever contact g lifts the pin i. 95 When the electro-magnet F lifts the armature lever G it establishes electrical connection between contact g and the ground connection and when in this position the armature lever is caught over the shoulder of the latch H 100 maintaining the ground circuit. The object in making the upper contact in the form of a movable pin i is to insure contact as the lever G rises over the shoulder h², the pin i following down the contact g irrespective of 105 slight variations in the position of lever G. When the weighted arm or arms are brought up and dropped over against the latch H, as indicated by dotted lines in Fig. 6, the catch h² is thrown back from its temporary support of lever G and the latter drops to the full line position seen in Figs. 6 and 7, allowing the ground circuit to be opened and stopping the motor. 110

I have shown two gravitating arms O and O¹. Only one is needed where the time of action of the revolving semaphore is one complete revolution of worm wheel N. This time can, however, be reduced by the use of two arms O and O¹ and using two pins n n¹ 120 placed diametrically opposite each other, one pin n being long enough to strike both arms and the other pin n¹ short enough to strike the one arm closest to the worm wheel only, as indicated by dotted lines. 125

I will now describe the complete operation of my signal, reference being had to the diagram Fig. 2. The three binding posts x, y, z, are arranged in the box D. The post x receives current from the generator and trolley wire 130

by wire *b*. From the point *x* the current divides, one part going through wire 13 to the semaphore light brushes *K* *J*¹ and wire 14 to the point 17; the other part going through wire 15 to the motor *M*, resistance *r* and wire 16 to the point 17. From 17 there are also two circuits. One goes through wire 18, the coils of electro-magnet *F* and wire 19 to binding post *g* and track switch contact *a* to the rail. The other goes from point 17 through lever *G*, contacts *g* and *I* and wire 20 to binding post *z* and ground wire *c* to the rail. The circuit 13, 14, 18, 19 is the initial starting circuit and this is made whenever the passing 10 car closes the track switch at *a*. Its effect is to close a ground circuit 20 by closing contacts *g* and *I*; the circuit being maintained closed by the holding latch *H* through the limited period of time during which the 15 semaphore is kept revolving, its bell ringing and its lamps illuminated. When the initial or starting circuit is opened by the car wheel leaving the depressible shoe, the electro-magnet is demagnetized so that when the 20 latch *H* is tripped after the predetermined time, the lever *G* falls and opens the ground circuit 20, *c*.

I do not confine my invention to the exact construction and arrangement of devices 30 shown and described, as these may be varied in many respects without departing from my invention, as set forth in the claims.

An important feature of my invention is to be found in the fact that the balanced and 35 somewhat heavy semaphore arms receive no shock or jar when stopped. This is due to the fact that while the gears *m*, *m*¹ *m*², turn the semaphore arms in one direction, said arms will continue to slowly revolve after 40 the motor stops, the worm *L* turning the worm wheel *N*, the spur gears and the armature of the motor until all parts come slowly to a standstill.

What I claim is:

- 45 1. An electric signal device, comprising a normally open electric circuit, a circuit closer closed by the passage of the car, an electric motor, balanced revolving semaphore arms, a series of diminishing spur gears connecting the motor to the shaft of the semaphore arms for reducing the speed from the motor to the revolving arms and also allowing the back transmission of power from the revolving arms to the motor shaft when the motor is out of action, an electro-magnet arranged in the normally open electric circuit, an armature switch for said electro-magnet having a contact for a shunt circuit and a shunt circuit made through the same to ground from the motor and tripping mechanism for opening the armature switch of the shunt circuit after a predetermined period, to give a limited-continuous revolution to the semaphore arms.
- 50 2. An electric signal device, comprising a

normally open electric circuit, a circuit closer closed by the passage of the car, an electric motor, balanced revolving semaphore arms, a series of diminishing spur gears connecting the motor to the shaft of the 70 semaphore arms for reducing the speed from the motor to the revolving arms and also allowing the back transmission of power from the revolving arms to the motor shaft when the motor is out of action, an electro-magnet 75 arranged in the normally open electric circuit, an armature switch for said electro-magnet having a contact for a shunt circuit and a shunt circuit made through the same to ground from the motor and tripping mechanism 80 for opening the armature switch of the shunt circuit after a predetermined period, to give a limited-continuous revolution to the semaphore arms, said means consisting of a revolving wheel bearing a pin and a loosely 85 hung gravity hammer hung upon the axis of the wheel and adapted to be lifted by said pin and to fall with a sharp impact against the tripping mechanism for the armature switch of the shunt circuit to open the latter. 90

3. An electric signal device, comprising a normally open electric circuit, a circuit closer closed by the passage of the car, an electric motor, balanced revolving semaphore arms, a series of diminishing spur gears 95 connecting the motor to the shaft of the semaphore arms for reducing the speed from the motor to the revolving arms and also allowing the back transmission of power from the revolving arms to the motor shaft when 100 the motor is out of action, an electro-magnet arranged in the normally open electric circuit, an armature switch for said electro-magnet having a contact for a shunt circuit and a shunt circuit made through the same 105 to ground from the motor and tripping mechanism for opening the armature switch of the shunt circuit after a predetermined period, to give a limited-continuous revolution to the semaphore arms, electric incandescent lamps arranged in the semaphore arms, two revolving insulated rings connected respectively to the terminal wires of the lamps and rubbing contacts arranged in the shunt circuit. 110

4. A revolving electric signal, consisting of an electro-mechanical motor mechanism, a hollow shaft bearing two insulated rub-rings with bearing contacts, a hollow radiating arm connected rigidly to the hollow shaft and 120 having an electric light box on the outer end and two circuit wires connected respectively to the two rub-rings and extending thence through the hollow shaft and the hollow radiating arm to the electric lamps of the light 125 box.

5. A revolving electric signal, consisting of an electro-mechanical motor mechanism, a hollow shaft bearing two insulated rub-rings with bearing contacts, a four-way pipe-cou- 130

- ding at the outer end of the hollow shaft, two opposite hollow radiating arms connected in the opposite ends of the pipe-coupling and bearing at their outer ends electric light boxes, two electric wires connected to the rub-rings and extending through the hollow shaft and through the opposite hollow arms to the electric lamps.
6. A revolving electric signal, consisting of an electro-mechanical motor-mechanism, a hollow shaft bearing two insulated rub-rings with bearing contacts, a four-way pipe coupling at the outer end of the hollow shaft, two opposite hollow radiating arms connected in the opposite ends of the pipe coupling and bearing at their outer ends electric light boxes, two electric wires connected to the rub-rings and extending through the hollow shaft and through the opposite hollow arms to the electric lamps and a detachable closure for the four-way coupling arranged coaxially with the shaft.
7. In an electric signal, the combination of an electro-magnet, a subjacent armature lever pivoted on a horizontal axis at one end and bearing a contact at the other end, a movable superimposed contact for the same, a tripping latch arranged in a vertical plane and having a catch to hold the armature lever and a time mechanism for tripping said latch.
8. In an electric signal, the combination of an electro-magnet, a subjacent armature lever pivoted on a horizontal axis at one end and bearing a contact at the other end, a movable superimposed contact for the same, a tripping latch arranged in a vertical plane and having a catch to hold the armature lever and a time mechanism for tripping said latch consisting of a revolving wheel bearing a loose hammer arm and a lift projection for lifting and dropping the hammer arm against the tripping latch.
9. In an electric signal, the combination with an electric motor and semaphore arm shaft having parallel axes; of a series of parallel spur gears having straight teeth, a casing inclosing the same, a rock-shaft journaled in the casing and having on one end inside the casing a crank arm connected to the spur gear and having on the outside of the casing a bell hammer and a gong bell inclosing the same.
10. An electric signal apparatus, comprising an electric motor and semaphore arm shaft having parallel axes, a train of gear wheels connecting the same, a worm located on the semaphore shaft, a superposed worm wheel with a loose gravitating hammer arm, an armature lever arranged at right angles to the semaphore shaft, an electro-magnet arranged above the same, a tripping latch for the same arranged in the path of the gravitating arm and terminal contacts controlled by the armature lever.
11. In an electric signal, the combination with an electric motor and semaphore arm shaft having parallel axes; of a series of parallel spur gears connecting the motor and semaphore shaft, an eccentric arranged upon the outer side of one of the spur gears, a bell hammer and bell, and means for connecting the bell hammer to the eccentric.

In testimony whereof I have affixed my signature in presence of two witnesses.

GEORGE W. PETTEY.
